FIG. 1

FIG. 2

Inventor

E. W. GUNTER

By Clarence A. O'Brien and Harvey B. Jackson Attorney

UNITED STATES PATENT OFFICE

133,547

DESIGN FOR A PIN OR SIMILAR ARTICLE

Edmo W. Gunter, Dexter, Mo.

Application June 23, 1942, Serial No. 107,316

Term of patent 7 years

To all whom it may concern:

Be it known that I, Edmo W. Gunter, a citizen of the United States, residing at Dexter, in the county of Stoddard and State of Missouri, have invented a new, original, and ornamental Design for a Pin or Similar Article, of which the following is a specification, reference being had to the accompanying drawing, forming part thereof.

Figure 1 is a front elevational view of a pin or similar article showing my new design, and Figure 2 is a top view.

I claim:

The ornamental design for a pin or similar article, as shown.

EDMO W. GUNTER.
